UNITED STATES PATENT OFFICE.

EDWARD P. WAGGONER, OF SYRACUSE, NEW YORK, ASSIGNOR TO THE A. A. GRIFFING IRON COMPANY, OF JERSEY CITY, NEW JERSEY.

DESIGN FOR A SHELL FOR GENERATORS.

SPECIFICATION forming part of Design No. 30,320, dated March 7, 1899.

Application filed May 18, 1898. Serial No. 592,224. Term of patent 14 years.

To all whom it may concern:

Be it known that I, EDWARD P. WAGGONER, of Syracuse, in the county of Onondaga, in the State of New York, have invented a new and useful Design for the Shell of a Generator, of which the following is a specification, reference being had to the accompanying drawings, showing a part thereof.

Figures 1 and 2 are respectively front and rear perspectives of the shell of a generator embodying my design.

The leading feature of my design consists of a substantially flat rectangular base extending from front to rear of the shell of the generator and similarly - extending bottom and top surfaces, the bottom surfaces curving outwardly and upwardly from the longitudinal sides of the base and the top surface curving outwardly and downwardly from its longitudinal center toward the upper sides of the bottom surfaces.

A is the base, B the bottom surfaces, and C the top surface. The base A extends from front to rear of the shell of the generator, is formed substantially flat and rectangular, and its opposite sides swell downwardly from their upper edges and are provided with lengthwise convex and concave surfaces a a', arranged one above the other. The bottom and top surfaces B B C also extend from front to rear of the shell of the generator, and the bottom surfaces B B are formed convex in cross-section and extend upwardly from the longitudinal sides of the base A. The top surface C curves outwardly and downwardly

in a plane convex in cross-section from its longitudinal center toward the upper sides of the bottom surfaces B and is united to said bottom surfaces by substantially flat and parallel side surfaces D. The front and rear faces E F of the shell of the generator are substantially flat and parallel, and the upper and lower extremities of the front face E are provided with raised ornamented surfaces e e'. The upper raised surface e is formed with a substantially straight lower edge and convex side and top edges and the lower raised surface e' is substantially rectangular. The upper and lower extremities of the rear face F are provided with a raised surface f and a depressed surface f', having its upper edge straight and its bottom and side edges formed substantially concave.

The shell of a generator embodying my design presents a characteristic and pleasing appearance, owing to the combined effect of the straight and curved lines and surfaces.

What I claim is—

The design for the shell of a generator, substantially as shown and described. 60

In testimony whereof I have hereunto signed my name, in the presence of two attesting witnesses, at Jersey City, in the county of Hudson, in the State of New Jersey, this 8th day of May, 1898.

EDWARD P. WAGGONER.

Witnesses:

N. R. MARVIN,
J. M. C. THOMAS.
